(57) **CLAIM**

The ornamental design for a light source module as shown and described.

DESCRIPTION

FIG. 1 is a perspective view of a light source module of the first embodiment of our new design;

FIG. 2 is a front view of a light source module of FIG. 1;

FIG. 3 is a rear view of the light source module of FIG. 1;

FIG. 4 is a top plan view of the light source module of FIG. 1;

FIG. 5 is a bottom plan view of the light source module of FIG. 1;

FIG. 6 is a right side view of the light source module of FIG. 1;

FIG. 7 is a left side view of the light source module of FIG. 1;

FIG. 8 is a perspective view of a light source module of the second embodiment of our new design;

FIG. 9 is a front view of a light source module of FIG. 8;

FIG. 10 is a rear view of the light source module of FIG. 8;

FIG. 11 is a top plan view of the light source module of FIG. 8;

FIG. 12 is a bottom plan view of the light source module of FIG. 8;

FIG. 13 is a right side view of the light source module of FIG. 8;

FIG. 14 is a left side view of the light source module of FIG. 8;

FIG. 15 is a perspective view of a light source module of the third embodiment of our new design;

FIG. 16 is a front view of a light source module of FIG. 15;

FIG. 17 is a rear view of the light source module of FIG. 15;

(Continued)

FIG. 18 is a top plan view of the light source module of FIG. 15;
 FIG. 19 is a bottom plan view of the light source module of FIG. 15;
 FIG. 20 is a right side view of the light source module of FIG. 15;
 FIG. 21 is a left side view of the light source module of FIG. 15;
 FIG. 22 is a perspective view of a light source module of the fourth embodiment of our new design;
 FIG. 23 is a front view of a light source module of FIG. 22;
 FIG. 24 is a rear view of the light source module of FIG. 22;
 FIG. 25 is a top plan view of the light source module of FIG. 22;
 FIG. 26 is a bottom plan view of the light source module of FIG. 22;
 FIG. 27 is a right side view of the light source module of FIG. 22; and,
 FIG. 28 is a left side view of the light source module of FIG. 22.
 The broken lines show portions of a light source module that form no part of the claimed design.
